DIRECTIONAL RADIO TRANSMITTING
SYSTEMMark L. MacAdam, Brockton, Mass., assignor to
Radio Industries Corporation, New York, N. Y.,
a corporation of New York

Application November 20, 1942, Serial No. 466,245

2 Claims. (Cl. 250—11)

1

This invention relates to a radio transmitting system employing two directional transmitting antennas suitably spaced apart and disposed parallel to each other on suitable fixed supports whereby a marked directional effect in the direction of the antennas or in any desired direction within a certain angle on either side of the azimuth of the antennas may be readily secured. It is a feature of the invention that the direction in which the signal energy is propagated may be readily changed without disturbing the conductors of which the antennas are composed.

In the illustrated embodiment of the invention, the antennas are rhombic antennas of the same size and similar in construction. When two such antennas are supplied with signal currents in such a manner that the current in one antenna is in phase with that in the other, the radiation fields of the antennas combine to produce a main resultant field which is markedly directional and extends in the azimuth of the antennas and in the sense toward which the antennas are directed. It has been found that if the phase of the current in one antenna is shifted slightly with reference to that in the other antenna, the resultant main radiation field may be shifted to either side of its original or center position depending upon the direction of the phase shift. It is a feature of the present invention that a control means is provided for securing such a shift in the resultant main radiation field with the result that the radiation field may be directed exactly in the azimuth of the antennas or exactly onto a desired region lying within a number of degrees on either side of said azimuth. It has also been found that the control means provided is effective even though the two rhombic antennas are not exactly similar in size and construction or if the transmission lines connecting the antennas to the final amplifying stages of the transmitter are not exactly similar; these variations in the two antenna paths being compensated for by shifting the phase of the current in one antenna with reference to that in the other by a suitable amount by means of the control means provided.

When it is desired to transmit a powerful radiation field to provide coverage over a distant territory, it is necessary to supply the antennas with considerable power as, for example, fifty kilowatts. The radio signals to be transmitted are built up to such a high power level by amplifying them in a plurality of vacuum tube amplifiers connected in cascade, such series of amplifiers comprising several intermediate amplifiers which amplify the signal at low power levels and driver

2

and final amplifiers which utilize high voltages and operate at high power levels. It is a characteristic feature of the present invention that the phase shift is secured by means of a device connected with the input circuit of one of the intermediate amplifiers where the power level is low. This arrangement contributes to the safety and convenience of operation of the system in that the operator of the control device, which effects the phase shift, is not exposed to the high voltage and currents which he otherwise would be if the phase shifting device were connected to one of the transmitting lines connecting the final high power amplifier to its antenna. Furthermore, the desired arrangement reduces the cost of construction substantially over what it would be if the control device were operated at a high power level where its parts would necessarily be massive to carry the heavy currents and would also have to be highly insulated.

Further objects of the invention will become apparent as the description thereof proceeds. For a better understanding of the invention reference is made to the following description taken in connection with the accompanying drawing, in which:

Fig. 1 is a schematic circuit arrangement of a directional radio transmitting system embodying the invention; and

Fig. 2 is a map of a portion of the earth in oblique azimuthal projection showing also approximate directional characteristic patterns adapted to be produced by the transmitter shown in Fig. 1.

Referring to the illustrative embodiment of the invention shown in Fig. 1, 10 denotes a crystal controlled vacuum tube oscillator, 11 an intermediate amplifier, 12 a modulator in which the amplified carrier currents are modulated in amplitude by the speech, music or other signals to be broadcast, and 13 an intermediate amplifier in which the modulated radio frequency signal currents are amplified. From the output of 13 the amplified signal currents are transmitted to a pair of rhombic antennas 14, 14' through the paths 15 and 16. The antennas 14, 14' are disposed parallel to each other at the desired azimuth and are spaced apart a suitable distance from each other to secure the desired resultant

main radiation field pattern. Each antenna is suitably supported in a stationary position on poles and may be constructed to transmit a large amount of power as, for example, 50 kilowatts.

Circuit path 15 is shown as comprising a variometer 17, an intermediate amplifier 18, a pair

of driver amplifiers 19 and final amplifiers 20, the output of both amplifiers 20 being supplied to one corner of antenna 14 through the transmission line 21. Circuit path 16 is similar in all respects to circuit path 15 except that the variometer 17 is omitted therein, its amplifiers being similar to those in path 15 and designated by the same reference numerals primed. It will be understood that variometer 17 may be omitted from circuit path 15 and included in path 16 instead without affecting the method of operation of the transmitting system.

Variometer 17 is illustrated as comprising a fixed winding 22 and a movable winding 23 which is rotated by a shaft 24 provided with a control knob 25. Shaft 24 carries a graduated dial 26, a suitable stationary index mark 27 being provided to indicate the dial reading. As illustrated dial 26 is preferably graduated in degrees of true bearing of the main resultant radiation field of the two antennas 14 and 14'. For monitoring the separate fields radiated by the antennas, a pair of monitor pickups 28, 28' are provided, one disposed in front of each antenna, the outputs of these pickups being transmitted to a phase monitor 29 of known type by a line 30, the monitor indicating the phase difference between the currents received on the pickups.

Assuming that it were desired to broadcast to either Buenos Aires or Rio de Janeiro from a transmitter located at Scituate, Mass., the similar rhombic antennas would be mounted so that they were directed in the direction OA, Fig. 2, to a region or point A midway between these cities. If the several elements of circuit path 15 are exactly similar to those of circuit path 16 and antenna 14 is exactly similar in size and construction to antenna 14', no correction need be applied by the variometer 17, since the currents supplied to amplifiers 18 and 18' will be in phase as will also the currents in antennas 14 and 14' so that the resultant main radiation field of the two antennas will be directed exactly at point A. If, however, the circuit paths 15 and 16 are not exactly balanced as, for example, transmission line 21 being slightly different in length or construction from transmission line 21', or antenna 14 being slightly different in size or construction from antenna 14', then the signal currents in antennas 14 and 14' will not be in phase and the resultant main radiation field will not be directed exactly to point A but to a region on one side or the other of this point. This unbalance between the circuit paths 15 and 16 will be indicated on the phase monitor 29 and may be compensated for by the operator adjusting the control knob 25 of variometer 17. This adjustment will make the current supplied to amplifier 18 lead or lag that supplied to amplifier 18' by the amount necessary to cause the azimuth of the main resultant radiation field to be moved in the direction of point A until the desired coverage is secured.

If now it is desired to broadcast to Buenos Aires in Spanish, the control knob 25 is rotated in such direction, for example, as to cause the current supplied to amplifier 18 to lag that supplied to amplifier 18'. This causes the current in antenna 14 to lag that in antenna 14', the amount of the lag being indicated on the phase monitor 29 and causes the azimuth of the resultant radiation field to be shifted in the direction of Buenos Aires. Such shifting may be continued until the direction has been shifted through an angle of

the order of 10 degrees before the two antenna fields get so much out of phase with each other that they start to separate and no longer reinforce each other. The phase shifting device shown thus provides means whereby the resultant main radiation field may be directed exactly in the direction of Buenos Aires as indicated by curve B, Fig. 2, and the desired region covered in a Spanish broadcast. The dial 26 of the variometer may be calibrated, as shown, in degrees of true bearing of the resultant radiation field so that the operator may readily direct the field in the desired direction or it could be calibrated in terms of degrees scanning of the radiation field.

If it is later desired to transmit a broadcast in the Portuguese language to Rio de Janeiro, it is only necessary for the operator to adjust the control knob 25 in the opposite direction until the phase of the signal current supplied to amplifier 18 leads that supplied to amplifier 18' by the necessary amount, as determined by the reading of phase monitor 29. The resultant main radiation field will then be directed towards Rio de Janeiro as illustrated by curve C, Fig. 2, and the broadcast may proceed in the usual manner. While the phase shifting device 17 has been illustrated as a variometer, it will be understood that a variable capacitive device or other known type of phase shifting network may be used instead.

I have described what I believe to be the best embodiments of my invention. I do not wish, however, to be confined to the embodiments shown, but what I desire to cover by Letters Patent is set forth in the appended claims.

I claim:

1. A radio transmitting system comprising, in combination, two similar spaced rhombic antennas disposed at substantially the same azimuth, two circuit paths connected to corresponding ends of said antennas and each comprising a plurality of vacuum tube amplifiers connected in cascade, and a control device connected to the input of an amplifying stage preceding the final stage of one path, said control device being adjustable to vary the phase of the amplified signal current in one antenna with reference to the phase of the amplified signal current in the other antenna during transmission to thereby vary the direction of transmission of the resultant radiation field of the two antennas and means connected to the first amplifying stages of said circuit paths for supplying the signal currents thereto, said final amplifying stage operating at a high power level and the amplifying stage preceding the final stage operating at a low power level.

2. The method of transmitting radio frequency signal currents simultaneously from two spaced similar rhombic antennas disposed at substantially the same azimuth which comprises the steps of generating the signal currents, amplifying in a plurality of cascaded amplifying stage the signal currents in two parallel paths, transmitting the amplified currents from one path to one antenna, transmitting the amplified currents from the other path to the other antenna, shifting the phase of the signal current applied to the input of a stage preceding the final stage of one path by an amount sufficient to change the direction of transmission of the main resultant radiation field of the two antennas by a substantial amount, while operating the amplifying stage preceding said final stage at a low power level and operating the final stage at a high power level.

MARK L. MACADAM.
